DENTURE

Samuel E. Linchitz, New York, N. Y.

Application January 22, 1934, Serial No. 707,722

12 Claims. (Cl. 32—4)

The present invention is concerned with artificial teeth particularly adapted to be removably secured to the gums within the mouth of the user by suction.

5 More particularly, however, the invention has to do with an improved roofless denture having means for disconnectably holding one or more normally expandible resilient pouches out of contact with the surfaces of the gum and spaced 10 therefrom.

In one aspect of the invention, the denture comprises a casing adapted to conveniently and disconnectably receive air expelling means in the form of collapsible pockets or pouches to 15 permit a palate or arch shaped portion of the denture to be held against the roof of the mouth.

According to the invention, the denture is provided with spaced casings suitably embedded or cast in the body thereof such that the material 20 of the body constitutes an intervening instrumentality between the surfaces of the gums and the innermost wall or complement of expandible and deflatable pouches or pockets removably confined and associated with respective casings.

25 As another aspect, the invention provides pouch means comprising complementary juxtaposed walls having their facing marginal portions appropriately secured as to form a unitary peripheral rim disconnectably mounted within a 30 continuous channel or groove of a pouch carrying member or casing previously anchored to and held by the body of the denture.

The invention has as a further aspect, the provision of a denture adapted to be disconnectably secured to the surface of the roof of the mouth by removably associated pouches each comprising of opposed elastic or complementary sections normally having their central portions widely separated to constitute an air receiving 40 chamber in which the air is initially compressed and subsequently slightly expanded to create a pneumatic force to hold the body of the denture to the surfaces of the gum.

The invention has as a further aspect the provision of a denture having spaced frames cast therein each to removably hold pouch means for disconnectably holding the denture to a gum of the mouth, the frames being interconnected by brace means to reinforce the denture.

50 The invention has as a further aspect, the provision of novel pouch means comprising complementary elastic walls or elements one of which is provided with relatively small spaced perforations disposed in registration with corresponding openings of an intervening part of the body

of the denture whereby upon the initial displacement of a companion and cooperating wall of the pouch means and subsequent release thereof the aforementioned intervening part of the body is held to the surface of the gum by suction. 60

Other aspects, objects, features and advantages of the invention may be better understood of the preferred embodiments hereinafter specifically described and although such embodiments are merely described as illustrative of the invention 65 and not to be considered as limitations thereon, the invention will be better understood from a consideration of such specific proceedings and teachings thereof and for this purpose and to aid the following specific description, reference 70 is made to the accompanying drawing in which:—

Fig. 1 is an elevational view of my improved denture according to the invention.

Fig. 2 is a section on the line 2—2 of Fig. 1.

Fig. 3 is a section on the line 3—3 of Fig. 1. 75

Fig. 4 is a sectional view of a slightly modified pouch receiving casing.

Fig. 5 is a view in perspective of my improved pouch.

The denture, according to the invention is generally designated 10 and may be made of any suitable moldable material employed in the art of artificial dentistry. Teeth as 11 are secured to the rim of the plate or denture and the latter is appropriately shaped to conform to the irregularities of the gum of the mouth as is well understood. As illustrated, the denture has been designed for removable attachment to a gum depending from the roof of the mouth. It should be understood, however, that the denture according to the invention may be so designed and cast for disconnectable association with the upstanding gums of the lower jaw. According to the showing of Figs. 1 and 2, the denture illustrated, is of the "roofless" type, to wit, the medial part of the palate or arch 12 thereof has been cut away. 85

Appropriately anchored or embedded within the lower part of each of the inclined sides of the palate or arch of the plate is a frame or casing, broadly designated 13. According to Fig. 3, the 100 casing comprises a continuously closed channel shaped rim 14 having spaced front and rear walls or margins 15 and 16 which are interconnected by a common side wall 17. These walls form an inwardly disposed continuous channel or groove to 105 removably receive and retain the relatively rectilinearly marginal rim portion 19 of a resilient and elastic pouch or pocket generally denoted 20.

To prevent movement of a frame or casing relative to the body of the plate, prongs as 18 extend 110

ing laterally of the sides 17 are provided and these prongs are anchored and embedded in the moldable material of the plate preparatory to its settling or hardening about the rear and side walls of 5 the casing or frame, it being noted that the moldable material of the plate is so cast as to have the lower surface thereof substantially flush with the outer surface of the wall 15 which according to the embodiment of Fig. 3 defines an uninterrupted intermarginal opening 21, in registration with a corresponding opening 22 formed by the rear wall 16 of the casing.

The pouch 20 comprises complementary parts or sections in the form of spaced elastic juxtaposed rubber or elastic walls 23 and 24 having their inside contiguous marginal faces suitably vulcanized or otherwise appropriately sealed, hence forming an air chamber 25.

The pouches according to the invention are 20 inserted in the frames or casings cast in the inclined sides of the denture plate, that is to say, marginal rim 20 of a pouch is removably held or retained within the continuous channel or recess of a casing. It will be noted that the upper elastic 25 complement 24 is provided with spaced openings or orifices 26 which are in registration with similar openings 27 in the arch of the plate, the top surface of complement 24 being held by its own resiliency against a relatively smooth arcuate 30 face 28 of the arch of the intervening part 29 of the plate.

Thus assembled, the lower complement of the pouch assumes a position to extend beyond the opening 21 as indicated by the dash and dot line 35 in Fig. 3. Stated in another way, normally, there is a relatively wide gap between the central parts of the arcuate complements of a respective pouch such that when the denture is not attached to a gum of the mouth, air will enter the chamber 25 between the complements through registering orifices 26 and 27, to hold the pouch relatively expanded.

When the denture is placed about the upper gum of the mouth and it is desired to secure the 45 same thereto, complement 23 is first pressed inwardly or towards the companion complement 24, hence the gap between the complements is reduced. If pressure be now removed from complement 23, the latter is held from completely 50 retracing provided opening 27 of the sides of the arch had been previously placed against the gum of the mouth, that is to say, a partial vacuum is formed, thus holding part 29 of the arch against the gum of the mouth by suction, the part 29 for 55 purposes of description may be considered as an intervening instrumentality between the gum of the mouth and the elastic and collapsible pouches, e. g. by reason of the intervening parts as 29, no part of the elastic pouches is in contact with the 60 gum of the mouth.

In the form according to Fig. 4, the rear wall of the casing or frame is in the form of arcuate plate 30 having spaced perforations 31 in alignment with openings 26 of the upper complement 65 of the pouch. Side 14 depending from plate 30 in association with front wall or inwardly extending flange 15 constitute rim means defining a channel as in the case of the form according to Fig. 3 for removably receiving rim 19 of a pouch 20. The casing according to Fig. 4 is also provided with prongs as 18 to prevent displacement thereof after having been cast in the body of the denture and the openings 31 thereof are in registration with openings as 27 of the intervening part 29 and if the pouch be inserted in

the rim, openings 31 would be in registration with openings 26.

To reinforce the intermediate part 12 of the palate the casings 13 on opposite sides of the arch are interconnected by a suitable integrally associated flat brace or metal strip 32 which is cast into the body of the denture and has its outside surface coincident with the lower surface of the crown.

In Fig. 1 the frames or casings on opposed sides of the arch are interconnected by a common reinforcing brace 32. If desired this brace may be omitted. Further it is within the scope of the invention to utilize the frame construction according to Fig. 4 in place of the frames of the type shown in connection with Fig. 3. If this substitution be made, a pair of spaced frames of the type shown in Fig. 4, if desired, may also be interconnected as is well apparent by a common intervening reinforcing brace as 32 although it is to be understood that the invention is not limited in this respect.

Many modifications of the invention will be apparent to those skilled in the art without departing therefrom or from the scope of the appended claims and since the foregoing has been given by way of example only for purposes of understanding of the principles underlying the invention, no unnecessary limitations should be inferred and/or understood and the appended claims should be construed as broadly as the state of the art permits.

I claim:

1. A denture comprising a palate having inclined perforated sides, a frame mounted in each side, and pouch means disconnectably associated with each frame.

2. A denture comprising a perforated palate, frame means attached to said palate, and pouch means disconnectably carried by said frame means.

3. A denture comprising a perforated palate, frame means attached to said palate, and pouch means disconnectably carried by said frame means comprising opposed complementary resilient walls, one of which includes a portion normally extending beyond said frame and the other thereof having perforations disposed in registration with the perforations of said palate.

4. A denture comprising a perforated palate, frame means attached to said palate and having a pouch receiving groove, pouch means comprising a pair of juxtaposed elastic walls defining a sealed peripheral rim, said rim being removably receivable in said groove, one of said walls having perforations disposed in registration with the perforations of said palate and the other wall of said pair having a central portion normally spaced from said perforated wall.

5. A denture adapted to be secured to the gum of a mouth by suction comprising a palate having an intermediate perforated part, a frame carried by said part, pouch means removably mounted in said frame comprising a pair of opposed and spaced elastic walls one of which includes perforations disposed in alignment with the perforations of said intermediate part of the palate and another thereof being adapted to be first displaced towards said perforated wall to compress the air between said walls and subsequently create a partial vacuum therebetween to hold said palate against the gum of the mouth.

6. A denture having a perforated palate, spaced frames carried by said palate, collapsible and expandible perforated pouch means removably

mounted in each frame and an intervening reinforcing member interconnecting said frames and secured to said palate.

7. A denture having a perforated palate, a frame secured thereto and having rim means, a perforated wall interconnecting said rim means and collapsible and expandible perforated pouch means removably mounted in said rim means.

8. As a new article of manufacture, a pouch comprising a pair of opposed elastic walls having their facing marginal portions sealed and intermarginal portions normally spaced apart to constitute an air chamber, one of said walls having one or more perforations, the other wall of said pair being adapted to be displaced towards said wall to expel air from said chamber.

9. As a new article of manufacture, a pouch comprising a pair of opposed elastic walls having their relatively rectilinear marginal portions sealed and their intermarginal portions normally spaced apart to constitute an air chamber, one of said walls having one or more perforations, the other wall of said pair being adapted to be displaced towards said wall to expel air from said chamber, said marginal sealed portions defining a continuous peripheral rim.

10. A denture adapted to be secured to the gum of a mouth by suction comprising a palate having an intermediate perforated part, a relatively elongated frame secured to said part, a perforated expandible and contractible pouch

removably mounted in said frame, said pouch having an imperforated wall normally extending beyond said frame and a perforated wall out of contact with said gum and disposed adjacent said perforated part.

11. A denture adapted to be secured to the gum of a mouth by suction comprising a palate having an intermediate perforated part, a relatively elongated frame secured to said crown and having a perforated wall disposed alongside of said intermediate perforated part, a perforated collapsible and expandible pouch removably mounted on said frame, said pouch having an imperforated wall having a central portion normally disposed beyond the limits of said frame and a perforated wall out of contact with said gum and disposed against the perforated wall of said frame, the perforations of said perforated walls and the perforations of said intermediate part being in registration.

12. A denture adapted to be secured to the gum of a mouth by suction comprising a palate having an intermediate perforated part, a frame secured to said part comprising a wall having perforations in communication with the perforations of said part, and a resilient member having a central portion normally spaced from said wall and comprising marginal portions disconnectably carried by said frame.
